UNITED STATES PATENT OFFICE.

MILTON A. FESLER, OF SAN FRANCISCO, CALIFORNIA.

CENTRIFUGAL OIL-BURNER.

1,255,592.

Specification of Letters Patent.

Patented Feb. 5, 1918.

Application filed October 24, 1916. Serial No. 127,403.

To all whom it may concern:

Be it known that I, MILTON A. FESLER, a citizen of the United States, residing at the city and county of San Francisco and State of California, have invented new and useful Improvements in Centrifugal Oil-Burners, of which the following is a specification.

This invention relates to a centrifugal oil burner.

10 One of the objects of the present invention is to provide a simple compact oil burner, in which the oil is atomized and projected in a forward direction with relation to the burner by the combined action of centrifugal force and air under pressure, and particularly to provide a rotating cup of novel construction by which atomization of the oil is effected.

Another object of the invention is to provide an anti-friction bearing for the cup together with means for delivering oil thereto, and also to provide means for forcing air both interior and exterior of the cup and simultaneously rotating the cup.

25 Further objects will hereinafter appear.

The invention consists of the parts and the construction and combination of parts as hereinafter more fully described and claimed, having reference to the accompanying drawings in which:—

Figure 1 is a central longitudinal section through the burner.

Fig. 2 is a plan view of a portion of the atomizing cup showing the relative position of the stationary and rotating turbine vanes.

Referring to the drawings in detail, A indicates a T fitting, on one end of which is secured a forwardly projecting nozzle 2. Mounted on the T fitting on the end opposite the nozzle, is a head 3 which is secured to the fitting in any suitable manner, and projecting through said head and supported thereby is a tubular bearing support 4. Suitably secured on the outer end of the tubular support, is a bearing head 5, and mounted in said head is a pair of anti-friction ball bearings 6, which support a tubular shaft 7 on the outer end of which is secured an atomizing cup 8. Secured on the inner end of the tubular member 4 as at 9, is a pipe 10 which passes through the tubular shaft 7 and en-

ters the inner end of the atomizing cup 8. This pipe together with the tubular member 4 being provided for the purpose of delivering fuel oil to the cup. Formed on the exterior surface of the cup 8, or suitably secured thereto, is a plurality of turbine vanes 11, and secured within the nozzle just ahead of the vanes 11, is a plurality of stationary vanes 12, and adapted to deliver air under pressure to the T fitting with connected nozzle 2 from a fan blower, or other source of air supply, is a pipe 13. Formed in the rear end of the cup is a plurality of perforations 14, and formed integral with the cup 15 and surrounding said perforations is an annular rearwardly projecting flange 15. The operation of the burner will be as follows:—

Air under pressure entering the T fitting A with connected nozzle 2, will pass through the stationary vanes 12 and impinge upon the vanes 11, causing these with connected cup 8 to revolve at a comparatively high speed. Oil is at the same time delivered to the tubular member 4 through the rear end, and is then conveyed through the pipe 10 directly into the atomizing cup, where it is discharged by centrifugal action. The high revolving speed of the cup produces sufficient centrifugal force to project the fuel oil in the form of a thin spray which is further broken up by the air discharging through the nozzle after passage through the turbine vanes. A highly combustible mixture is in this manner produced by the combined action of the centrifugal force and air under pressure and as the air pressure is sufficiently great to overcome the centrifugal action of the atomizer, it will readily be seen that a combustible mixture consisting of oil, vapor and air, will be projected in a forward direction with relation to the nozzle. A considerable portion of the air is also caught by the annular rearwardly projecting flange 15 and forced through the perforations 14 directly into the cup, in this manner supplying additional air through the center of the cone shaped flame, which has proven a great benefit so far as combustion is concerned.

Running parallel with the tubular member 4 is a lubricating oil supply tube 17. This is connected at one end with a lubricating

cup mounted on the head 3, and the opposite end with an oil duct 18 formed in the bearing head 5 which delivers the lubricating oil directly to the anti-friction ball bearings 5 shown. This manner of lubricating the revolving parts provided, is exceedingly efficient and reliable, as the well produced in the bearing head 5 permits the revolving parts to be amply supplied with a lubricant 10 at all times.

The burner here shown is exceedingly simple and compact in construction. All unnecessary revolving parts and bearings have been eliminated, in this manner reducing friction to a minimum, and the necessity of constant repair and replacing of parts. The burner is particularly adapted for handling low grade fuel oils as the centrifugal action of the cup together with the force 20 of the internal and external discharge air columns, permits the fuel to be broken up into highly atomized vapor which is readily ignited the moment it enters the furnace. The provision of the intake opening 13 25 shown, permits a whole battery of burners to be quickly connected and placed in position under a single boiler if desired, and as each oil and air connection is provided with a valve, independent adjustment as far as 30 each burner is concerned, may be obtained.

The materials and finish of the several parts of the burner may be such as the experience and judgment of the manufacturer may dictate.

35 I wish it understood that various changes in form, proportions and minor details of construction may be resorted to within the scope of the appended claims, and that I do not wish to limit myself to the specific design or construction here shown.

Having thus described my invention, what I claim and desire to secure by Letters Patent is:—

1. In a centrifugal burner, the combination of a casing, an oil discharge and distributing cup mounted in the axis of the casing for rotation, the outer discharge end of the cup forming with the adjacent mouth of the casing an annular orifice for the discharge of a film of air around the cup to commingle with the oil discharged from the cup, means for delivering oil into the cup, a series of blades mounted on the exterior of the cup and constituting a fan, and a series 55 of fixed direction blades mounted on the casing exteriorly to the cup and adjacent to the rotatable fan blades on the cup.

2. A centrifugal oil burner comprising a casing adapted to be connected with a source 60 of air supply under pressure, an air discharging nozzle on the casing, a tubular supporting member secured in the casing and extending into the nozzle, a bearing head on the outer end of said member, a hollow

shaft journaled in said bearing head, an 65 atomizing cup secured on the hollow shaft, a pipe secured in the outer end of the tubular member extending through the hollow shaft and communicating with the inner end of the atomizing cup, said tubular member 70 and pipe forming a stationary conduit for the delivery of fuel oil to the cup, and means on the cup actuated by the air discharging through the nozzle for rotating the cup.

3. A centrifugal oil burner comprising a 75 casing adapted to be connected with a source of air supply under pressure, an air discharging nozzle on the casing, a tubular supporting member secured in the casing and extending into the nozzle, a bearing head on 80 the outer end of said member, a hollow shaft journaled in said bearing head, an atomizing cup secured on the hollow shaft, a pipe secured in the outer end of the tubular member extending through the hollow shaft and 85 communicating with the inner end of the atomizing cup, said tubular member and pipe forming a stationary conduit for the delivery of fuel oil to the cup, a set of stationary turbine vanes secured in the nozzle 90 and surrounding the cup, and turbine vanes formed on and surrounding the cup adjacent the stationary vanes.

4. A centrifugal oil burner comprising a 95 casing adapted to be connected with a source of air supply under pressure, an air discharging nozzle on the casing, a tubular supporting member secured in the casing and extending into the nozzle, a bearing head on the outer end of said member, a hollow shaft 100 journaled in said bearing head, an atomizing cup secured on the hollow shaft, a pipe secured in the outer end of the tubular member extending through the hollow shaft and communicating with the inner end of the 105 atomizing cup, said tubular member and pipe forming a stationary conduit for the delivery of fuel oil to the cup, means on the cup actuated by the air discharging through the nozzle for rotating the cup, and means 110 for passing a part of said air through the cup.

5. In a centrifugal oil burner, a casing, a hollow shaft journaled in the casing for rotation, an oil distributing cup on the hollow 115 shaft and discharging from the end of the casing, a set of stationary turbine vanes secured in the casing and surrounding the cup, and turbine vanes formed on and surrounding the cup adjacent to the stationary 120 vanes, said stationary vanes and rotatable vanes arranged in co-operative relation, whereby the stationary vanes direct the air currents to the rotary vanes and the latter discharge a film of air around the cup.

6. In an oil burner, the combination with an air discharging nozzle, of an atomizing cup journaled in the nozzle, means for ro-

tating said cup, means for delivering fuel oil to the cup, a plurality of perforations formed in the inner end of the cup and an annular rearwardly projecting flange formed
5 on the cup and surrounding the perforations to deflect a part of the air discharging through the nozzle through the cup.

In testimony whereof I have hereunto set my hand in the presence of two subscribing witnesses.
